UNITED STATES PATENT OFFICE.

LAURENCE E. TOPHAM, OF SWAMPSOCT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

STOP MECHANISM.

Application filed July 12, 1917. Serial No. 180,115.

To all whom it may concern:

Be it known that I, LAURENCE E. TOPHAM, a citizen of the United States, residing at Swampscott, in the county of Essex and State of Massachusetts, have invented certain new and useful Improvements in Stop Mechanism; and I do hereby declare the following to be a full, clear, and exact description of the invention, such as will 10 enable others skilled in the art to which it appertains to make and use the same.

The invention relates to mechanism for uniformly stopping a machine with the driven parts in a predetermined position.

It is the object of the invention to provide a novel and improved mechanism which will operate efficiently and uniformly in stopping the driven parts of machines the speed of which may vary at the time the 20 mechanism comes into action.

To this end the invention contemplates the provision of speed reducing means acting to gradually retard the driven parts before they reach their final stopping position, the 25 retarding effect of which is controlled by the speed of such parts at the time the stopping is to be effected, the retarding effect being increased by increasing the intensity or the duration with relation to the movement of the parts of the action of the retarding means with an increase in the speed, and being reduced by reducing the intensity or duration of the action of the retarding 30 means, with a reduction in the speed. The retarding action is thus controlled to secure a gradual slowing down of the driven parts as they come to stopping position, whatever 35 their speed at the time the stopping is to be effected. It is preferred to employ a friction 40 brake as the means for retarding or retarding and stopping the driven parts, and to vary its retarding effect by varying the period or interval in the movement of the parts of its activity in accordance with the speed, 45 although this construction and specific mode of operation is not essential to the broader features of the invention. The period during which the retardation or slowing down of the driven parts continues is preferably 50 controlled by a cam, the position and timing of which with relation to the movement of the parts is varied by a centrifugal governor, and this construction constitutes

a feature of the invention which is not confined in its application to mechanisms in which a retarding means is applied when the driving power is thrown off, but may be embodied in mechanisms in which the resistance of the operating mechanisms of the machine acts as the means for retarding 60 or slowing down the machine when the power is thrown off.

The various features of the invention will be readily understood from an inspection of the accompanying drawings and the following detailed description of the mechanism illustrated therein.

In the drawings, Figure 1 is a side elevation showing a mechanism embodying the invention in its preferred form; Fig. 2 is a 70 sectional detail through the axis of the stud which supports the clutch operating lever and other parts of the mechanism; Fig. 3 is a sectional elevation on line 3, Fig. 1; Fig. 4 is a sectional view on line 4, Fig. 3; 75 and Fig. 5 is a view similar to Fig. 3, showing the parts in a different position.

In the drawings the invention is shown embodied in a mechanism for driving and stopping a shaft 2 from which the operating mechanisms of a sewing or other machine may be driven. The mechanism for driving the shaft during the operation of the machine comprises a wheel 4 which is secured to the flange of a sleeve 6 which is in turn secured to the shaft. The wheel is provided with a clutch face 8 arranged to be engaged by a clutch face 10 on a constantly rotating driving pulley 12 which is loosely mounted on the sleeve 6. The pulley 12 may be moved on the sleeve to engage or disengage the clutch face, or to vary the speed of the driven shaft, through a clutch operating arm 14, the upper end of which is provided with a cam face 16 90 engaging a bearing block 18 on the pulley, and the lower end of which is secured to the hub 20 of a lever 22. The end of the lever 22 may be connected through a rod 24 with an operating treadle (not shown), through which the operator may control the engagement and disengagement of the driving clutch member and the operation of the stopping mechanism. The clutch operating lever 22 is held in clutch disengag- 100 105 ing position by a spring 26 which normally

holds the stop screw 28 on the lever in engagement with a stop lug 30 on a fixed bracket 32.

The mechanism shown for retarding and stopping the shaft 2 when the driving clutch is disengaged by the release of the lever 22 comprises a brake shoe 34 arranged to engage the rim of the wheel 4, and a stop dog 36 movable into and out of the path of a stop lug 38 secured to the wheel. The brake shoe and stop dog are secured on an arm 40 which is pivotally supported upon a stud 42 upon which the clutch operating lever 22 is also mounted. The arm 40 is normally supported in position with the brake shoe out of engagement with the wheel 4 and the stop dog 36 out of the path of the stop lug 38, as indicated in Fig. 5, by a stop screw 44 carried by the bracket 32 and arranged to engage a lug 46 on the upper end of the arm. The means for applying the brake and bringing the stop dog into active position when the power is thrown off by the release of the lever 22 comprises a lever 48 loosely mounted on the hub of the arm 40, and a latch link 50, one end of which is pivoted to the upper end of the arm 40, and the other end of which is provided with a hook 52 adapted to engage a shoulder 54 on the lever. The link is drawn in a direction to engage its hook end with the shoulder on the lever 48 by a spring 56 which connects the link with a pin on the bracket 32. The upper end of the lever 48 is arranged to be engaged by a cam 58 carried on the shaft 2, and operating to apply the brake and render the stop dog active when in engagement with the upper end of the lever. When the driving clutch is engaged, the latch link 50 is disengaged from the lever 48, and the lever is held out of the path of the cam 58 by a block 60 adjustably secured to the upper end of an arm 62 formed on the clutch operating lever 22. The latch link is held in its raised disengaged position by engagement with the upper end of the block, as indicated in Fig. 5. When the lever 22 is released to disengage the driving clutch, it swings into the position indicated in Fig. 3, and the arm 62 moves to the right in Figs. 3 and 5, thus releasing the latch link 50 and permitting the lever 48 to move toward the shaft 2 under the influence of the spring 64. The latch link rides on the shoulder 54 on the lever 48 until the shoulder passes to the right of the hook 52 on the link, when the hook passes down to the left of the shoulder and into position to connect the lever with the arm 40. Now when the cam 58, during the rotation of the shaft 2, acts upon the lever 48, the movement of the lever to the left operates the arm 40 to apply the brake shoe 34 to the wheel 4, and to bring the stop dog 36 into the path of the stop

lug 38, so that the movement of the shaft 2 is gradually retarded, and the shaft finally brought to rest with the lug 38 in engagement with the stop dog, as indicated in Fig. 3. When the lever 22 is depressed to again engage the driving clutch, a cam surface on the block 60 acts to lift the latch link 50, thus disconnecting the arm 40 from the lever 48, so that the brake shoe and stop dog are free to return to their inactive position. The block 60 also engages the lever 48 and moves it out of the path of the cam 58, as indicated in Fig. 5.

In order that the braking effect of the brake shoe 34 may vary in accordance with the speed of the shaft 2 at the time when the driving clutch is disengaged, the cam 58 is so mounted on the shaft 2 that its position circumferentially of the shaft, and therefore the timing of its action on the brake applying lever 48, may be varied in accordance with the speed of the shaft. In the construction shown, the cam 58 is pivotally mounted on a sleeve 66 which is in turn mounted on the sleeve 6. The cam is provided on its inner edge with a pawl 68 arranged to engage ratchet teeth 70 formed on the sleeve 6. The position of the sleeve 66 and of the cam 58 on the shaft 2 is determined by two centrifugal governor arms 72 pivoted on the wheel 4 and provided with gear segments 74 engaging a gear 76 formed on the sleeve 66. The governor arms are acted upon by springs 78 which tend to hold them substantially in the position indicated in Fig. 3.

When the shaft 2 is being driven, the cam 58 will be thrown into the position indicated in Fig. 5 by centrifugal action, its outward swinging movement being determined by the engagement of its forward end with a stop surface on the sleeve 66. The sleeve and cam are therefore free to be moved about the shaft in either direction by the swinging movement of the centrifugal governor arms 72. When the shaft is being driven at slow speed the governor arms and the cam 58 will occupy substantially the position indicated in Fig. 3, and the shaft will come into stopping position shortly after the cam has acted to apply the brake. If the shaft is being driven at high speed when the clutch lever 22 is released to disconnect the power, the centrifugal governor arms and the cam 58 will occupy substantially the position indicated in Fig. 5 when the cam 58 engages the brake applying lever 48, and the brake will be applied and held in braking engagement with the wheel 4 for a comparatively long interval before the parts come to stopping position. The extent to which the governor arms advance the cam on the shaft 2, and consequently the period during which the brake is applied before the parts come to

stopping position will depend upon the speed at which the shaft is rotating when the stop mechanism is thrown into action by the release of the clutch shifting lever

- 5 22. The position of the cam 58 on the shaft 2 is determined by the engagement of the pawl 68 on the cam with the ratchet teeth 70 when the cam engages the lever 48, the cam being locked in position on the shaft 10 by the pawl and ratchet teeth during the subsequent revolution of the shaft, and while it is being slowed down and stopped by the retarding and stopping devices.

By the above mechanism the retarding effect of the brake is varied in accordance with the speed of the shaft 2 and the parts driven therefrom at the time the stopping is to be effected, so that the parts will be uniformly brought to rest in a predetermined 20 position without regard to the speed at the time the retarding and stopping mechanism comes into action. The parts may be so designed and adjusted that the shaft will be brought to rest by the brake at a uniform 25 point in its rotation, but it is preferred to provide stopping devices such as the stop dog 36 and lug 38 which come into engagement and determine the final stopping position, since with this construction any slight 30 variation in the stopping position, due to variations in the action of the brake, may be avoided. In the latter case the brake so retards the shaft prior to the engagement of the stopping devices that they effect the final 35 stopping without undue shock or strain on the parts, the increased braking interval when stopping at high speed serving to overcome the increased momentum of the parts, so that the engagement of the stopping 40 devices occurs under substantially uniform conditions.

The mode of operation of the mechanisms shown is briefly as follows: During the driving the lever 22 is depressed and the parts 45 are substantially in the position shown in Figure 5. When the shaft 2 is to be stopped, the lever 22 is released and is raised by its spring into the position indicated in Figure 3. By this movement the block 60 is carried 50 to the right, permitting the lever 48 to move into the path of the cam 58 and releasing the latch 50 so that it will hook onto the lever and connect the arm 40 with the lever, as indicated in Figure 3. Now the cam 58, 55 the position of which circumferentially of the shaft is controlled by the governor arms 72, acts on the lever 48 to apply the brake 34 and to bring the stop 36 into the path of the stop 38. The interval during which the 60 brake is applied will depend upon the position of the cam 58 which, in turn, depends upon the speed of the shaft at the time when the stop mechanism is thrown into operation and the shaft will be brought to rest uniformly whatever its speed.

While the invention has been shown and described as embodied in a mechanism in which the speed reducing means is in the form of a friction brake, it will be understood that this construction is not essential 70 to the broader features of the invention, and that so far as certain features of the invention are concerned the speed reducing means may be of any suitable form, and that under certain conditions the resistance of the moving parts may act as the speed reducing means.

Having explained the nature and object of the invention, and specifically described one form of mechanism in which it may be embodied, what is claimed is:—

1. A stop mechanism having, in combination, means for gradually retarding the driven parts until they come substantially to stopping position, and mechanism for 85 regulating the retarding means by the speed of the driven parts to vary its retarding effect in accordance with the speed at the time the retarding means is rendered active.

2. A stop mechanism having, in combination, means for gradually retarding the driven parts until they come substantially to stopping position, and mechanism for varying the duration of the retarding interval 90 in accordance with the speed of the driven parts at the time the retarding means is rendered active.

3. A stop mechanism, having, in combination, means for reducing the speed of the driven parts substantially to stopping position, and means for varying the point in the movement of the driven parts at which the speed reduction begins in accordance with the speed of the driven parts at the time the stopping is to be effected.

4. A stop mechanism having, in combination, speed reducing means rendered active in stopping the driven parts, and means for regulating the point in the movement of the driven parts at which the speed reduction 110 begins by the speed of the driven parts at the time they are to be stopped.

5. A stop mechanism, having, in combination, a driven shaft, means for reducing the speed of the shaft prior to stopping it, and 115 means for varying the point in the rotation of the shaft at which the speed reduction begins in accordance with the speed of the shaft at the time the stopping is to be effected.

6. A stop mechanism, having, in combination, a brake for reducing the speed of the driven parts, and means for varying the point in the movement of the driven parts at which the brake is applied in accordance 125 with the speed of the driven parts.

7. A stop mechanism, having, in combination, means for retarding the driven parts as they come to stopping position, a cam, moving in unison with the driven parts for 130

initiating the retarding action, and a centrifugal governor for controlling the cam to vary the retarding interval in accordance with the speed of the driven parts at the time the cam becomes active.

8. A stop mechanism, having, in combination, means acting when the power is thrown off to retard the driven parts as they come to stopping position, a cam for rendering the retarding means active, and a centrifugal governor for controlling the timing of the cam.

9. A stop mechanism having, in combination, a brake for reducing the speed of the driven parts, a cam moving in unison with the driven parts for applying the brake, and a centrifugal governor for regulating the point in the movement of the driven part at which the cam applies the brake.

10. A stop mechanism, having, in combination, driving mechanism for driving and for varying the speed of the driven parts, normally inactive mechanism for continuously reducing the speed of the driven parts until they come substantially to stopping position, and means for varying the speed reducing interval preceding the final stopping in accordance with the speed of the driven parts.

11. A stop mechanism, having, in combination, treadle controlled mechanism for driving and for varying the speed of the driven parts, mechanism for continuously reducing the speed of the driven parts until they come substantially to stopping position rendered active in throwing out the driving mechanism, and means for varying the speed reducing interval preceding the final stopping in accordance with the speed of the driven parts.

12. A stop mechanism, having, in combination, a driven shaft, a cam mounted to turn on the shaft, a centrifugal governor connected with the cam to determine its position on the shaft, and speed reducing and stopping mechanism controlled by the cam.

13. A stop mechanism, having, in combination, a driven shaft, a cam mounted to turn on the shaft, a centrifugal governor connected with the cam to determine its position on the shaft, a lever arranged to be operated by the cam, a brake shoe carrier, a latch link for connecting the lever and carrier, and a power controlling lever provided with means for disengaging the link and holding the lever out of the path of the cam.

14. A stop mechanism, having, in combination, a driven shaft, speed reducing means, a controller cam mounted to turn on the shaft for applying the speed reducing means, a centrifugal governor connected to the cam to determine its position circumferentially of the shaft, and means for locking the cam in position on the shaft while active.

15. A stop mechanism, having, in combination, a driven shaft, speed reducing means, a cam for applying said means mounted to turn on the shaft and having a limited radial movement, a pawl on the cam, and teeth on the shaft cooperating with the pawl to lock the cam during its action on the speed reducing means.

16. A stop mechanism, having, in combination, treadle controlled mechanism for driving and for varying the speed of the driven parts, means rendered active in throwing out the driving mechanism for continuously retarding the parts until they come to stopping position, and mechanism for varying the retarding effect of said means in accordance with the speed of the driven parts at the time the driving mechanism is thrown out.

17. A stop mechanism, having, in combination, driving mechanism, normally inactive and continuously acting speed reducing means for bringing the driven parts to substantially a state of rest rendered active when the driving mechanism is thrown out, and a centrifugal governor for varying the retarding effect of the speed reducing means in accordance with the speed of the driven parts.

18. A stop mechanism, having, in combination, driving mechanism, a brake for reducing the speed of the driven parts, and mechanism for applying the brake when the driving mechanism is thrown out including a centrifugal governor for varying the braking action of the brake in accordance with the speed of the driven parts.

19. A stop mechanism, having, in combination, mechanism for continuously retarding the driven parts when rendered active, and mechanism for automatically varying the retarding effect of such mechanism in accordance with the speed of the driven parts to bring them substantially to a state of rest at a predetermined point regardless of the speed at the time the stopping is to be effected.

LAURENCE E. TOPHAM.
